W. C. GRUSS

HAIR CURLER

Filed Oct. 16, 1922

W. C. Gruss INVENTOR
BY *Victor J. Evans*

WITNESS:
E. George

ATTORNEY

UNITED STATES PATENT OFFICE.

WALTER C. GRUSS, OF PITTSBURGH, PENNSYLVANIA.

HAIR CURLER.

Application filed October 16, 1922. Serial No. 594,920.

To all whom it may concern:

Be it known that I, WALTER C. GRUSS, a citizen of the United States, residing at Pittsburgh, in the county of Allegheny and 5 State of Pennsylvania, have invented new and useful Improvements in Hair Curlers, of which the following is a specification.

This invention contemplates the provision of a bobbed hair curler wherein use is made 10 of a plurality of independent curlers arranged in end to end relation, and associated by means of flexible connections, so that the device as an entirety, can be rolled or twisted in the hair in the proper manner, after the ends of the hair are clamped 15 in said rollers.

The nature and advantages of the invention will be better understood when the following detailed description is read in connection 20 with the accompanying drawing, the invention residing in the construction, combination, and arrangement of parts as claimed.

In the drawing forming part of this application, like numerals of reference indicate similar parts in the several views, and wherein:—

Figure 1 is a view in elevation of the device forming the subject matter of the invention.

Figure 2 is a fragmentary view partly in section, showing one of the curlers with the clamping element separated therefrom.

Figure 3 is a perspective view of one of 35 the clamping elements.

Figure 4 is a sectional view taken on line 4—4 of Figure 1.

Figure 5 is a similar view taken on the line 5—5 of Figure 1.

The device herein illustrated embodies a plurality of independent curlers, which are arranged in end to end relation, and suitably connected together, so that the device in its entirety can be rolled or twisted in the hair in the usual well-known manner for the purpose above stated. It is of course to be understood that the length of the device can be varied by using the greater or less number of curlers. The device is held in the hair when in use by means of strings or the like 10, which are arranged at the ends of the device as illustrated in Figure 1.

Each curler includes a tubular body portion 11 provided with a longitudinal bore 12, and these curlers are arranged in end to end relation, and connected together by

means of a coiled spring 13, or any other suitable flexible element which is passed through the bores 12. Each body portion 11 is formed adjacent one end with an annular groove 14, and its opposite end with openings 15 arranged at diametrically opposite points, for purposes to be presently described.

Associated with each body member 11 is a 65 clamping element indicated at 16, and of the outline illustrated in Figure 3. This clamping element is of semi-cylindrical contour in cross section to correspond to the curvature of the body member 11, which it 70 partly embraces when arranged in active position. One end of the clamping element 16 is provided with inwardly extended lugs 17 which are received by the openings 15 of the body member, in a manner which provides 75 for pivotal movement of the clamping element upon the body member. The opposite end of this clamping element is provided with oppositely curved extensions 18, projecting from the opposed sides of the clamping 80 element, and adapted to be received by the groove 14 above mentioned. These extensions possess the desired degree of resiliency to spring over the body member 11 and hold the clamping element in clamping 85 relation with said body member, when the device is in use.

In practice, the ends of the hair are passed about the body portions 11 of the various independent curlers, and the hair 90 clamped in this position between the body portions 11 and the clamping elements 16, which when clamped in position, partly embraces the body members 11, and are held fixed relatively therethrough, through the 95 instrumentality of the resilient extensions 18 arranged in the groove 15. As above stated, the independent curlers are arranged in end to end relation as illustrated in figures both 1 and 2, and are associated by 100 means of a flexible connection of any suitable character, so that the device in its entirety can be properly flexed, and one or more of the curlers rolled or twisted independently of the adjacent curlers as the occasion 105 may demand incident to the use of the article. I preferably make use of the coiled spring above referred to, which not only holds all the curlers associated in end to end relation, but also provides, the necessary 110 flexible connection between the adjacent curlers. In order to prevent the hair from

being caught in the flexible connections, or otherwise entangled thereabout, a portion of the spring between the adjacent ends of the respective curlers is covered with a flexible sleeve, 21, which may be constructed from any suitable material, preferably thin rubber. After the ends of the hair have been clamped to the various independent curlers, the device in its entirety is then 10 rolled or twisted in the hair in the usual manner and retained in this position for an appreciable length of time, by means of the strings 10 until the hair has been properly curled.

15 While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:—

1. A hair curler of the character described 25 comprising a plurality of independent curlers arranged in end to end relation, and flexible connections arranged between the adjacent ends of said curlers for the purpose specified.

30 2. A hair curler of the character described comprising a plurality of independent curlers arranged in end to end relation, flexible connections interposed between the adjacent ends of said curlers, and tying elements arranged at the ends of the device as and for the purpose specified.

35 3. A hair curler of the character described comprising a plurality of independent curlers arranged in end to end relation, flexible connections arranged between said curlers, and each curler including a hollow body portion, and a clamping bar mounted for pivotal movement and adapted to be arranged within the body portion in clamping 45 ing positions.

40 4. A hair curler of the character described comprising a plurality of independent curlers arranged in end to end relation, flexible connections between the adjacent ends of the curlers, and sleeve-like members enclosing the flexible connections as and for the purpose specified.

45 5. A hair curler of the character described comprising a plurality of independent curlers arranged in end to end relation, each curler including a hollow body portion having reduced ends, a clamping bar pivoted in one end and adapted to be arranged around the body portion in clamping position, the free end of said bar being frictionally engaged by the other reduced extremity of the body portion and holding said bar in a clamped position, and flexible con-

nections arranged between the ends of the adjacent curlers as and for the purpose 65 specified.

6. A hair curler of the character described comprising a plurality of independent curlers arranged in end to end relation, coiled springs arranged between the ends of the adjacent curlers, and providing a flexible connection therefor, and sleeve-like members surrounding said coiled spring.

7. A hair curler of the character described comprising a plurality of independent curlers arranged in end to end relation, coiled springs interposed between the ends of said curlers and providing a flexible connection therefor, each curler including a hollow body portion, a clamping bar pivoted at one end of the body portion, and adapted to be arranged around the latter in a clamping position, means for holding said bar in a clamping relation with said body, and a sleeve-like member enclosing each spring.

8. A hair curler of the character described comprising a plurality of independent curlers arranged in end to end relation, flexible connections between the adjacent ends of the respective curlers, each curler including a body portion, a clamping element pivoted upon the body portion at one end thereof, and arranged parallel therewith in clamping position, and means carried by the clamping element and engaging the body portion for holding said parts fixed relatively when the element is in active position.

9. A hair curler of the character described comprising a plurality of independent curlers arranged in end to end relation, each curler including a hollow body portion, a flexible element passed through all of said curlers, and providing a flexible connection between the adjacent ends of the curlers, said curlers being slightly spaced apart, a clamping element pivoted on the body portion of each curler, and adapted to be arranged parallel therewith in clamping position, and means for holding the clamping element in clamped position.

10. A hair curler of the character described comprising a plurality of independent curlers arranged in end to end relation, said curlers being slightly spaced apart, flexible connections between the adjacent curlers, each curler including a tubular body portion, a clamping bar pivoted at one end of the body portion and designed to partly embrace the latter when arranged parallel therewith in clamping position, and resilient extensions projecting from said clamping element and designed to engage the body of the curler to hold the parts fixed relatively when in use.

In testimony whereof I affix my signature.
WALTER C. GRUSS.
